UNITED STATES PATENT OFFICE.

ALBERT PIHL, OF MURRAY, UTAH, ASSIGNOR TO GEORGE F. BORKMAN, OF SALT LAKE CITY, UTAH.

TELEPHONE RECEIVER.

Application filed December 27, 1922, Serial No. 609,191. Renewed February 9, 1926.

To all whom it may concern:

Be it known that I, ALBERT PIHL, a citizen of the United States, and resident of Murray, in the county of Salt Lake and 5 State of Utah, have invented certain new and useful Improvements in Telephone Receivers, of which the following is a specification.

My invention relates to an improved telephone receiver of what is known as the watch case type, and is particularly adapted for wireless telephony although not limited in its use thereto.

An object is to provide a receiver which 15 will be simple in structure but very efficient in operation, and which may be readily assembled.

Another object is to arrange the pole pieces and armature so that the latter will 20 be very sensitive to slight currents and may be easily operated.

Other objects will be apparent from the following detailed description and the appended claims.

25 In the drawings:

Figure 1 is a cross section through the receiver in its case with parts shown in elevation.

Figure 2 is a face view of the receiver 30 with the cover of the case removed.

Figure 3 is a bottom plan of the receiver removed from the case.

Figure 4 is a detached view of one pole piece and the armature carried thereby, the 35 two parts being shown disassembled.

To a ring 1 is secured a permanent magnet 2 of the shape shown in Figure 3, the ring and magnet being secured together by bolts 3 and 4. The top pole piece 5 fits in a 40 cut out portion of the permanent magnet and is held in position between the magnet and the ring 1 by the bolt 4. The free end of this pole piece supports the core 6 as clearly shown in Figure 1 around which fits 45 the coil 7 wound between two fibre discs 8 and 9.

A bottom pole piece 10 has the form shown in Figure 4, and is attached in a cut out of the magnet 2 by the bolt 3. It will 50 thus be noted that the two bolts 3 and 4 hold together the ring, and both pole pieces, and that the pole pieces hold the coil in position between them. The pole piece 10 is approximately T-shaped, and the bolt 3 55 passes through an opening 11 in one end

thereof. The other end of the pole piece 10 is formed with opposite pairs of offset ears 12 and 13. Between the offset 12 is a projecting lug 14 having a hole 15 therein.

An armature 16 of the general form 60 shown in Figure 4 has attached to it in any desired manner a spring portion 18 having a reversely bent end provided with a hole 18. A bolt 19 which passes through the holes 15 and 18 fastens the spring portion 65 17 of the armature to the pole piece 10. The armature is provided with cone shaped pivot members 20 which are mounted in corresponding depressions in the offset ears 13, thus pivoting the armature for free 70 movement. At the end thereof the armature has a hole 21 through which passes a wire or bolt member 22 which is attached at its other end in the usual manner to the diaphragm 23. This diaphragm fits within 75 an annular depression in the ring 1 so that it lies flush with the face of the ring.

Binding posts 24 are provided which are carried by the ring 1 and may be of the split type or of any other desired form. It 80 may be seen that all of the above described parts are carried as a unit by the ring 1, and this unit is preferably inclosed within a case 25 having a cover 26 provided with central air openings 27. This case and cover member 85 are preferably formed of hard rubber or similar insulating material.

I claim as my invention:

1. A telephone receiver comprising a ring member, a U-shaped permanent magnet carried by said member, pole pieces attached to the ends of the magnet and extending toward each other in substantially parallel planes, a coil retained in position between the free ends of the pole pieces and having its axis at substantially right angles to said planes, an armature pivotally carried by one of said pole pieces, a diaphragm carried by the ring member, and means connecting the armature to the diaphragm. 190

2. A telephone receiver comprising a ring member, a permanent magnet carried by said member and having free ends, pole pieces attached to the ends of the magnet and extending toward each other in substantially parallel planes and having their free ends overlapping, a coil mounted between the free ends of the pole pieces and having its axis at substantially right angles to said free ends, an armature pivotally supported by 110

one of said pole pieces, a diaphragm, and means connecting the armature to the diaphragm.

3. A telephone receiver comprising a ring member, a permanent magnet carried thereby, pole pieces attached to the magnet and having free ends extending toward each other in substantially parallel planes, a coil supported between the free ends of the pole pieces and having its axis at substantially right angles to said planes, an armature pivotally supported by one of the pole pieces, a diaphragm, and means connecting the armature to the diaphragm.
- 15 4. A telephone receiver comprising a supporting member, a permanent magnet carried by said member and having free ends, two pole pieces attached to said magnet and having free ends extending toward each other, a coil supported between the free ends of the pole pieces and also between the free ends of the permanent magnet, a diaphragm carried by said supporting member, an armature pivotally carried by one of the pole pieces, and means connecting the armature with the diaphragm.
- 20 5. A telephone receiver comprising a supporting member, a permanent magnet carried thereby, a pole piece attached at one end to the magnet and having a core at the other end, a coil surrounding said core, a second pole piece attached to the magnet and extending over said coil, an armature pivotally attached to the second pole piece and extend-
- 25

ing adjacent said core, a diaphragm, and means connecting the armature to the diaphragm.

6. A telephone receiver comprising a supporting member, a permanent magnet carried thereby, two pole pieces attached to said magnet and having free ends extending towards each other in overlapping parallel relation, an armature pivotally mounted intermediate its ends in one pole piece, a spring member connected to the armature at one end and to the pole piece at its other end, a diaphragm, and means for connecting the free end of the armature to the diaphragm.

7. In a telephone receiver a pole piece provided with two pairs of offset ears, an armature lying therebetween and pivoted to one pair of ears, a spring connected to one end of the armature and to the pole piece and means for connecting the other end of the armature to a diaphragm.

- 50 8. A telephone receiver comprising a permanent magnet and extending at an angle thereto in substantially overlapping parallel relation, a coil, two pole pieces attached to the magnet, a core for the coil carried by one pole piece, an armature pivotally mounted intermediate its ends in the other pole piece, and spring means connected to one end of the armature and to the pole piece.

In testimony whereof, I have hereunto subscribed my name.

ALBERT PIHL.
